This invention relates to control means, more particularly to methods and apparatus for automatically controlling the drawing or drafting of elongate material by means of drafting rolls through which said material is fed.

A variety of materials are fabricated by passing the material through apparatus which serves to draw the material into an elongate shape. Thus, in the fabrication of textile yarns, the raw material is passed through a series of draw frames, spinning frames, or the like, to produce elongate yarn of desired thickness. The term "spinning" will be here employed to designate all of the fabrication steps to which textile fibers are subjected in order to form the final yarn product.

In the spinning of textile materials, a variety of problems arise in controlling the drafting of the textile material so as to provide yarn, sliver, or roving of uniform weight per unit length. Means are known for automatically controlling the weight per unit length of the fabricated yarn. These means generally employ a measuring device to continuously measure the weight per unit length of the yarn. These continuous measurements are averaged, and then the instantaneous deviations are obtained by comparing the instantaneous measurements with the average. A signal is produced depending on the magnitude of these deviations, and the signal is amplified and employed to control the speed of drafting. The measuring components employed are either electrical, optical or pneumatic. The generally available measuring components are however not stable over a sufficiently long time period so that any average range within which it is desired to maintain quality control usually is unmaintainable over the entire production run resulting in a long term quality variation. This may of course, be overcome by frequent calibration of the measuring device, which of course requires uneconomical down-time. Where long term variations are ignored, conventional control apparatus is adequate, but this is not always feasible.

It has been proposed to eliminate some of the above noted problems by ignoring long term variations. This is feasible since during the spinning operation the greater portion of deviations are of a short term nature, with a lesser number being of medium term nature, and only an insignificant number of variations being of a long term nature. Where these long term variations are ignored, some difficulties still arise in that control action is not adequate at start-up of spinning apparatus. Additionally, the average value against which deviations are compared requires fairly complex circuitry in order to permit averaging over a significant time period.

It is with the above problems in mind, that the present means have been evolved, means permitting the automatic control of material drafting operations to produce a substantially uniform product, and with the controlling action compensating for deviations of a long term, medium term, or short term nature.

It is accordingly a primary object of this invention to provide an improved control for regulating the operation of material fabricating equipment in response to quality variations of the material.

Another object of the invention is to provide quality control means regulating material drafting operations so

2

as to eliminate long term, medium term, and short term variations in said material.

It is also an object of this invention to provide an improved method for controlling textile spinning operations so as to produce yarn of substantially uniform quality.

It is also an object of the invention to provide means compensating long term disturbing influences on the measuring element of a control system.

10 These and other objects of the invention which will become apparent in the following specification and claims are achieved by provision of measuring means in combination with the drafting rolls of spinning equipment, so that a signal is transmitted from said measuring means indicative of the quality of the material passing therethrough. Generally measurements of material thickness are made in said measuring means.

One of the conventionally employed plurality of pairs of drafting rolls is operated at a constant speed and another of the pairs of drafting rolls is operated at a variable speed. Means are provided indicating the differential in angular speed between an angular speed proportional to that of the variable speed drafting rolls and an angular speed of that of the constant speed drafting rolls. 20 This differential angular speed is fed through a reducing means to position converting means which puts out an electrical signal indicative of the aforementioned speed differential. The electrical signal provided by the position converting means is fed to compensating means along with a measuring signal from said measuring means, where these signals are compensated, whereby the long term variations of the measuring signal which are due to disturbing influences on said measuring device are eliminated.

35 Both a method and apparatus as will become heretofore more apparent are provided embodying the instant inventive concept.

The specific structural details of several embodiments 40 of the invention, and their mode of functioning will be made most manifest and particularly pointed out in clear, concise, and exact terms in conjunction with the accompanying drawings, wherein:

45 FIG. 1 is a schematic representation of the drafting zone of a textile machine, showing the novel control apparatus schematically as arranged in combination therewith;

FIG. 2 is a diagrammatic illustration of another embodiment of the control apparatus in which the position converting means are embodied in a potentiometer forming part of an electrical bridge;

FIG. 3 is an alternative embodiment of the invention in which the position converting means is embodied in a tuning condenser;

50 FIG. 4 illustrates an embodiment of the invention in which the measuring means are of an optical nature;

FIG. 5 is a schematic detail view similar to FIG. 1 showing more clearly the mechanical inter-relationship between the components, and

55 FIGS. 5a and 5b show respectively a series and parallel circuit for compensator 2.

60 Referring now more particularly to the drawings, like numerals will be employed to designate like parts.

In the embodiment of the invention illustrated in 65 FIGS. 1 and 5, measuring means in the form of a condenser 1 are positioned to measure the material passing into the drafting area of textile spinning apparatus S. Condenser 1 is electrically coupled to compensator 2 which comprises an electrical network. The output of this compensator 2 is fed through schematically illustrated amplifier A where the signal is amplified and fed to a drive 4 in which the electrical energy output of amplifier

3 is converted into rotational mechanical energy for driving a pair of variable speed drafting rolls 5 and 6.

A pair of drafting rolls 7 and 8 are driven at a relatively constant speed, and the material 9 to be drafted is fed through measuring device 1, the constant speed rolls 7 and 8, and variable speed rolls 5 and 6 as illustrated.

The angular speed of the variable speed drafting rolls 5 and 6 is transmitted through gear 10 to reduction gear 11 to differential gear 12. It will also be observed that constant speed rolls 7 and 8 are also coupled through gearing to differential gear 12. Differential gear 12 is mounted for rotation in cage 12'. Cage 12' may rotate about an axis perpendicular to the axis of gear 12, and as is apparent from FIGS. 1 and 5 is free to rotate on the shafts extending between reduction gear 11 and its associated bevel gear in the cage; and the unidentified pinion at the left and its associated bevel gear in the cage, cage 12' being fixedly secured to pinion 13' which rotates therewith. Any movement of the cage 12' of differential gear 12 is transmitted through pinion 13' to gear 13, the angular speed of which is transmitted through spur gears 14 and 15 to position converting means in the form of potentiometer 16 in which slider arm 17 assumes a position between terminals 18 and 19 of the potentiometer. Stops 20 and 21 arranged respectively adjacent opposite terminals of the potentiometer 16 limit the movement of slider 17. These stops 20 and 21 are preferably made in the form of limit switches forming part of a subsidiary circuit (not shown) which controls an alarm signal indicating the existence of a long term disturbance.

Phase shifter 30 is arranged in the circuit leading from measuring condenser 1 to compensator 2. Phase shifter 30 is essentially an R-C network which lags the measuring signal from the condenser for a purpose to be made hereinafter more apparent.

A tacho-generator 31 is coupled to the shaft of gear 13 whereby the rotational energy of gear 13 is transmitted in the form of electrical energy to compensator 2 to form a closed servo-loop.

In the embodiment of the invention illustrated in FIG. 2, the position converting means in the form of potentiometer 16 is arranged with terminals 18 and 19 directly in the circuit of measuring condenser 1 (rather than across an independent voltage source as in the FIGS. 1 and 5 arrangement) along with measuring bridge 26. The bridge voltage resulting from this arrangement is applied directly across phase shifter 30, the output of which is fed to amplifier 3.

In the embodiment of the invention illustrated in FIG. 3, potentiometer 16 is replaced by tuning condenser 22 the capacity of which is variable by means of rotor arm 23 which is coupled to rotate with gear 15. In this embodiment of the invention, the combination of tuning condenser 22 and, measuring plate condenser 1 forms the compensator 2. The output of the compensator 2 as formed by the combination of tuning condenser 22 and plate condenser 1 is fed through phase shifter 30 to amplifier 3 as in the FIG. 1 embodiment.

In the embodiment of the invention illustrated in FIG. 4, the measuring means employed are of an optical nature comprising a radiation source 28 and radiation receivers 24 and 29. The amount of radiation passing from source 28 to receiver 24 is variable by means of scanning aperture 25 which is coupled to gear wheel 15 so that the position of gear wheel 15 determines the amount of screening effected by aperture 25, while the amount of radiation passing to receiver 29 is determined by the material 9.

Element 2 in FIGS. 3 and 4 serves as a compensator.

Operation

The aforesigned apparatus is employed for controlling the quality of material during the drafting opera-

tion. As most fully illustrated in FIGS. 1 and 5, a material 9 such as a textile material is drawn through the measuring device 1 by means of a pair of constant speed drafting rolls 7 and 8 turning at a constant angular speed n_2 .

5 speed n_2 . A measuring signal U_1 proportional to the weight of the material in said measuring device at any given instant is fed through time delay circuit 30 to compensator 2. Additionally, an electrical signal U_3 is fed from the position converting potentiometer 16 to the compensator 2. The compensator provides as an output differential signal U_4 representing the differential between signals U_1 and U_3 . Differential signal U_4 is fed through amplifier 3 where it is amplified and delivered to drive 4.

10 Drive 4 drives variable speed rolls 5 and 6 at an angular speed n_3 which averages approximately 10 to 50% higher than the constant angular speed n_2 of the pair of constant speed rolls 7 and 8. This average angular speed n_3 is that speed at which the desired drafting of material 9 takes place.

15 Upon the occurrence of an increase in weight per unit length of the material 9 above the desired average value, measuring signal U_1 from measuring device 1 is increased producing an increased output U_4 from compensator 2 and a corresponding increase in the speed of drive 4 and speed n_3 of the pair of variable speed drafting rolls 5 and 6. With this increase in speed the material is drafted down to desired thickness.

20 If on the other hand the weight of the textile material 9 becomes less than the desired average value, the measuring signal U_1 is reduced, with a corresponding decrease in the electrical energy fed to drive 4, and a resultant decrease in speed n_3 of variable speed drafting rolls 5 and 6. This decrease in drafting roll speed provides less draft and the material increases in weight.

25 By means of gears 10 and 11, the variable angular speed n_3 of the pair of drafting rolls 5 and 6 is transformed to a first variable angular speed n_1 . This angular speed n_1 represents the angular speed n_3 of variable speed drafting rolls 5 and 6 reduced by a drafting factor or the change of speed of variable speed rolls 5 and 6 necessary to provide the proper draft of the material to produce the desired average weight. Thus when the desired average draft is obtained, the angular speed n_1 is equal to the angular speed n_2 . This variable angular speed n_1 and the angular speed n_2 are both imparted to differential gear 12 functioning as a subtracter. It will be obvious to those skilled in the art that the same subtracting function may be accomplished by means of a planetary gear or the like. The cage 12' of gear 12 and the pinion 13 which is driven by said cage 12' remains stationary so long as the angular speeds n_1 and n_2 are equal. Upon a change of angular speed n_1 with respect to the angular speed n_2 , gear cage 12' is rotated at angular speed n_4 causing pinion 13 to change the position of slider arm 17 of potentiometer 16 through spur gears 14 and 15, the output of which has an angular speed n_5 . Thus potentiometer 16 will permit an electrical signal U_3 to pass to compensator 2, said electrical signal U_3 being determined by the position of cage 12'. Potentiometer 16 thus serves as position converting means.

30 Spur gears 14 and 15 serve to reduce the motion transmitted from cage 12' so that slider arm 17 is limited in its motion. The magnitude of the reduction ratio effected by spur gears 14 and 15 determines the time factor required for readjustment of average material thickness, and should therefore be adjustable, as will become hereinafter more apparent. This time factor is obtained so as to compensate for the time required to move slider arm 17 which, as will be apparent, varies depending on the reduction between the angular speed differential n_4 which is assumed to be constant and the reduced angular speed differential n_5 .

35 The voltage across potentiometer 16 between its terminals 18 and 19 has a magnitude U_2 . The voltage be-

tween arm 17 and terminal 19 has a magnitude U_3 which as previously mentioned is fed to compensator 2. The angle α subtended by arm 17 between terminal 19 and the arm 17 will be variable by

U_3 is related to U_2 in the following manner:

$$U_3 = U_2 \frac{\alpha}{\alpha_0}$$

During start-up arm 17 is positioned in such a way that signal U_3 corresponds in magnitude to that of measuring signal U_1 . Thereafter arm 17 follows the movements of pinion 13. There is a slight time delay between the positioning of arm 17 through $\Delta\alpha$. This angle $\Delta\alpha$ represents the integrated value of the angular speed n_5 over the time interval $\Delta t = t_2 - t_1$ namely:

$$\Delta\alpha = 2\pi \int_{t_1}^{t_2} n_5 dt$$

The signal U_3 as noted is fed to compensator 2.

During normal undisturbed operation, the variations in weight of textile material 9 produce short and medium term variations above and below the average value of measuring signal U_1 . The resultant differential produces a variation in output signal U_4 from compensator 2 which as previously discussed serves to vary the speed of variable speed rolls 5 and 6.

If a long term disturbing influence occurs, measuring signal U_1 changes positively with respect to signal U_3 with the result that a positive output signal U_4 is emitted from compensator 2 producing an increased angular speed in drafting rolls 5 and 6. This produces motion of cage 12' causing arm 17 to move through an angular displacement $\Delta\alpha$ whereby the magnitude of signal U_3 increases. If the long term disturbing influence continues then arm 17 eventually reaches stop 20 and will actuate a suitable alarm device, either lights, a stop motion, or an audible signal.

Phase shifter 30 is provided to interpose a time delay between the transmission of signal U_1 from the measuring device to the compensator so that the compensating action provided by a variation in material thickness will not begin to take place until that portion of the material which produced the measuring signal U_1 will have passed from the measuring zone to the drafting zone between rolls 7 and 8, and 5 and 6 respectively.

The linearity of control characteristics is improved by provision of tacho-generator 31 which serves to provide a closed circuit servo-loop in which the feed back signal U_5 generated by tacho-generator 31 which is proportional to the differential angular speed n_4 serves to eliminate the effects of drafting roll torque on the angular speed n_4 . The reversible rotation of gear 13 and tacho-generator 31 constitutes a conventional velocity closed loop servo-mechanism. The signal U_5 is dependent upon the direction and speed of rotation or velocity of gear 13, and thus of cage 12' of the differential gear. This signal U_5 is fed back to the compensator 2 in opposition to the first electrical signal U_1 from measuring device 1.

In the operation of the alternative embodiments of the invention, substantially the same functions are attained. As previously noted merely minor substitutions of components has been provided.

In the FIG. 2 embodiment, the position of potentiometer slider arm 17 directly determines bridge switching, so that the effect of long term variations is compensated. In the FIG. 3 embodiment, the long term variations of signal U_1 are compensated by a change in the setting of condenser 22 while short term variations produce a desired drafting change.

In the embodiment of FIG. 4 the screening effected by aperture 25 in response to long term variations, as indi-

cated by movement of gear 15, modifies the signal passing to compensator 2.

It is thus seen that a novel means of automatically controlling the drafting of materials has been provided in which long term variations and short term variations are all accommodated, and any inertial effects, or the like of the mechanism, are substantially mitigated in the control action.

The above disclosure has been given by way of illustration and elucidation and not by way of limitation and it is desired to protect all embodiments of the invention within the scope of the appended claims.

What is claimed is:

1. Means for controlling material drafting operations between a first pair of drafting rolls and a pair of variable speed drafting rolls, said means comprising: measuring means positioned before said first pair of drafting rolls to detect variations in the material passing thereto; compensating means to which a signal from said measuring means is fed; subtracting means coupled to the drafting rolls providing a signal indicative of the difference in angular speed between that of the first pair of drafting rolls and the variable speed drafting rolls, the difference signal being fed to said compensating means; reducing means interposed between the variable speed drafting rolls and said subtracting means and means directing a control signal from said compensating means to a drive for said variable speed drafting rolls, whereby the long term variations due to disturbing influences on the measuring means are eliminated.

2. Means for controlling material drafting operations between a first pair of drafting rolls and a pair of variable speed drafting rolls, said means comprising: measuring means positioned before said first pair of drafting rolls to detect variations in the material passing thereto; compensating means to which a signal from said measuring means is fed; subtracting means coupled to the drafting rolls providing a signal indicative of the difference in angular speed between that of the first pair of drafting rolls and the variable speed drafting rolls, the difference signal being fed to said compensating means, generating means coupled to said subtracting means to produce a signal indicative of the correction of drafting roll speed, said signal being fed to said compensating means and means directing a control signal from said compensating means to a drive for said variable speed drafting rolls, whereby the long variations due to disturbing influences on the measuring means are eliminated.

3. Means for controlling material drafting operations between a first pair of drafting rolls and a pair of variable speed drafting rolls, said means comprising: measuring means positioned before said first pair of drafting rolls to detect variations in the material passing thereto; subtracting means coupled to the drafting rolls providing a signal indicative of the difference in angular speed between that of the first pair of drafting rolls and the variable speed drafting rolls, compensating means to which the last named signal, along with the measuring signal are fed; time delay means interposed between said measuring means and said compensating means for delaying the signal from the former in its passage to said compensating means; reducing means interposed between said variable speed drafting rolls and said subtracting means to produce a signal indicative of the correction of drafting roll speed, said signal being fed to said compensating means; and means directing a control signal from said compensating means to a drive for said variable speed drafting rolls, whereby the long term variations due to disturbing influences on the measuring means are eliminated.

4. Control apparatus for regulating material drafting operations between a first pair of drafting rolls and a pair of variable speed drafting rolls, said apparatus comprising: a measuring device positioned before said first pair

of drafting rolls to detect variations in the material passing thereto; a compensator electrically coupled to said measuring device receiving measuring signals therefrom; a subtractor coupled to the drafting rolls and indicating the difference in angular speed between that of the first pair of drafting rolls and the variable speed drafting rolls; a position converter coupled to said subtractor providing an electrical signal indicative of the difference obtained from the subtractor, said signal being fed to said compensator; and an amplifier coupled to said compensator from which a control signal is fed to the drive for said variable speed drafting rolls.

5. Apparatus as in claim 4 in which a phase shifter is interposed between said measuring device and said compensator to delay the transfer of the electrical signal from said measuring device, whereby the material will be in the drafting zone at the time the control signal has effect.

6. Apparatus as in claim 4 in which a tacho-generator is coupled to said subtractor and the output of said generator is fed to said compensator, whereby inertial effects will be minimized.

7. Apparatus for automatically controlling drafting systems to prevent faulty control actions due to long term disturbing influences, said apparatus including a first pair of rolls operating at speed n_2 , and a second pair of variable speed drafting rolls operating at speed n_3 , said apparatus comprising: a mechanical subtractor in which the difference between an angular speed n_1 of a gear rotating at a speed proportional to the variable angular speed n_3 and angular speed n_2 is determined; position

5 converting means to which the output n_4 of the subtractor is fed, reduced by a gear to speed n_5 , said position converting means producing an electrical signal U_3 ; a measuring device arranged to measure the material being fed to the drafting rolls, said device producing a measuring signal U_1 ; a compensator to which the measuring signal U_1 and signal U_3 are fed, said compensator delivering a control signal U_4 for controlling operation of the variable speed rolls, whereby long term variations of the measuring signal U_1 produced by the measuring device due to disturbing influences on said measuring device are eliminated.

10 8. Apparatus as in claim 7 in which a tacho-generator is arranged in combination with said subtractor, and a signal from said tacho-generator is fed to the compensator, whereby load variations will have minimal effect on control operation.

15 9. Apparatus as in claim 7 in which the position converting means comprise a potentiometer.

10 10. Apparatus as in claim 7 in which the measuring device comprises an electromagnetic radiation source; a sensing member; and means for screening the radiation.

15 11. Apparatus as in claim 7 in which said position converting means include a tuning condenser.
